[57] CLAIM

The ornamental design for an optical coupler for coupling a television camera to a surgical headband, substantially as shown and described.

DESCRIPTION

FIG. 1 is a top, front and right side perspective view of an optical coupler for coupling a television camera to a surgical headband showing our new design; FIG. 2 is a left side elevational view thereof; FIG. 3 is a right side elevational view thereof; FIG. 4 is a front elevational view thereof; FIG. 5 is a rear elevational view thereof; FIG. 6 is a top plan view thereof; FIG. 7 is a bottom plan view thereof; and FIG. 8 is a front and right side perspective view thereof, shown coupled to a surgical headband.

The broken line showing of the surgical headband in FIG. 8 is for illustrative purposes only and forms no part of the claimed design.
